UNITED STATES PATENT OFFICE

2,559,027

CHAMBER POT FOR CHILDREN

Eduardo Miralta-Seix, Barcelona, Spain

Application January 7, 1949, Serial No. 69,811
In Spain (Utility Model) February 6, 1948

1 Claim. (Cl. 4—141)

1

The present invention relates to an improved chamber-pot for children.

It is known that the greatest inconvenience which chamber-pots for children offer, is the circular contour of the borders which press in the flesh and cause discomfort, preventing children from sitting the necessary time on the chamber-pot. Furthermore, the circular form does not prevent, but many times causes the contents to flow out of the vessel, all this constituting a nuisance and trouble.

The applicant has devised a new chamber-pot, after an anatomical study of the seating parts of the child in contact with said pot, resulting in a form contour of a seat which is technically correct and hygienical, not causing any discomfort to the child and supporting it under the thigh and avoiding that the contents flow out to the exterior, due to the special form.

Another feature of the present invention is the provision of a support against possible falls backwards which are so frequent with the ordinary chamber-pots. This support is constituted by a square-formed chock or brace, which at the same time serves as lug, this providing a practical, aesthetical and hygienical whole.

For a better understanding a sheet of drawings accompanies the present specification, showing a case of realisation which is only given by way of example.

Figure 1 is a side-view, in perspective, of the invention;

Figure 2 is a plan-view of the opening or seat of the invention; and

Figure 3 is a front-view, in elevation, of the same invention.

The present invention consists of a container, moulded from synthetic resin or other suitable material, the opening or seat of which forms an essentially oval elongated contour, of which the posterior zone 1 is nearly a half-circumference which is united by the tangential concave lines L, to a frontal zone or spout 2, the seat being formed by the upper rims of the chamber-pot, curved towards the outside, so that they constitute a convex or half-round curved contour.

The posterior portion of the chamber-pot has a support against possible back-falls, comprising a brace 3, which at the same time is a lug which may adopt different forms, with or without an opening.

Spout 2 is a lip similar to that of a jar, by means of which the pot is easily emptied.

2

The external form may vary in a compatible manner with the characteristic features described.

The invention within its essentiality may be carried out in other variations, to which the claimed protection will equally extend. It may, therefore, be manufactured in any form, or size, and employing any suitable material, all this being comprehended within the spirit of the claim.

Having now particularly described and ascertained the nature on my invention, I declare that what I claim is:

An improved chamber-pot for children, of lengthened contour of its seat, wherein the rim of the said lengthened contour is not in a plane but corresponds to a sinuous surface relative to a vertical plane passing through the major axis of the vessel, the depression being adjacent the widest or central portion adjacent the rear and the upwardly inclined portion adjacent the forward portion, while the rim converges forward of the enlarged body section on either side and terminates in a narrow pouring spout or lip for the purpose of adapting same in anatomical respect to the gluteal region of the child's body, a support on said chamber-pot externally thereof at the rear portion and in the direction of its longitudinal axis, the lower edge of said support coinciding with the chamber-pot's plane of support and extending rearwardly in a substantially flat plane therewith, said support having an opening transversely thereof constituting a handle for the chamber-pot.

EDUARDO MIRALTA-SEIX.
